UNITED STATES PATENT OFFICE.

ALEXANDER LEE HARRISON, OF UNION CITY, TENNESSEE.

PRESSER-FOOT FOR SEWING-MACHINES.

1,145,989.

Specification of Letters Patent. Patented July 13, 1915.

Application filed May 5, 1914. Serial No. 836,474.

To all whom it may concern:

Be it known that I, ALEXANDER LEE HARRISON, a citizen of the United States, residing at Union City, in the county of Obion and State of Tennessee, have invented certain new and useful Improvements in Presser-Feet for Sewing-Machines; and I do hereby declare the following to be a full, clear, and exact description of the invention, such as will enable others skilled in the art to which it appertains to make and use the same.

My invention relates to improvements in sewing machines, and particularly to that part of sewing machines known as presser feet. The present improvements being especially adaptable for use in connection with machines employed in the sewing of material which has been previously treated with a water proofing or like substance.

It has been found that after fabric has been treated with a water proofing compound or other adhesive substance, that the same is sewed and made into different forms with extreme difficulty, owing to the fact that the needle or needles of the machine after passing through the goods a comparatively few number of times, becomes gummed with the water proofing or like substance thereby destroying the feed and tension of the machine and also greatly reducing the speed thereof. In fact it has been found to be almost impossible to work with goods of the character described, in a satisfactory manner without in some way overcoming the objections above noted.

It is, therefore, the object of this invention to construct a presser foot provided with means whereby the disarrangement of the feed and tension of the machine is avoided, and at the same time a high rate of speed maintained throughout the sewing operation.

With this and other objects in view which will become apparent from the following description, this invention consists of a presser foot provided at its forward end with means whereby oil or other lubricant is fed continuously and automatically to the needle or needles of the machine, thereby preventing any gumming thereof; any disarrangement of the feed or tension of the machine, or any reduction in speed of the same.

For the purpose of explaining my invention I have illustrated in the accompanying drawings, a satisfactory reduction of the

same to practice, but the important features thereof may be varied, and hence it is to be understood that the invention is not limited to the specific organization shown and described.

In the accompanying drawings, Figure 1 is a side elevation of a presser foot provided with my improvements. Fig. 2 is a front elevation. Fig. 3 is a top plan. Fig. 4 is a bottom plan.

In the embodiment of the invention disclosed in the accompanying drawings, 5 designates the shank of the presser foot, which is adapted to be connected in any suitable manner to a presser bar of the usual type. The shank 5 is shown provided integrally with a fulcrum block 6, said fulcrum block 6 extending between lugs 7 positioned on the foot plate 8, the same being held in pivotal engagement therewith by means of a transverse pivot pin 9. The foot plate 8 may be of any desired form, and is shown in the drawings provided with the usual needle apertures or slots 10 and the upturning outer portion 11 adapted to engage and gradually guide the goods smoothly under the needle or needles of the machine.

Mounted preferably in the vertical plane upon the outer portion 11 of the foot plate 8, is a socket member 12, preferably of conical form, and open at its end portions, said socket member 12 being adapted to receive and frictionally retain therein an absorbent medium, 13, such as felt, cotton or the like. As will be seen from Fig. 1 the socket member 12 is slightly beveled at its lower end 14 in order to conform substantially to the contour of the outer upturned portion 11 of the foot plate 8.

In actual practice the absorbent medium, 13, is saturated with oil or other lubricating substance and is then placed in the socket member 12, substantially filling the same. It will thus be seen that as the goods, previously treated with a water proofing substance or the like, pass under the foot plate 8, they will receive automatically, through the forces of gravity and capillary attraction a constant supply of the lubricant from the socket member 12. The goods thus oiled will, upon coming into contact with the needle or needles of the machine, lubricate the same, thus preventing an accumulation thereon of the adhesive, water proofing substance. It has been found that through the

use of this device as above described, an approximate speed of 1,400 revolutions a minute can be maintained without any dis-
5 arrangement of the feed or tension of the machine. It will be noted from the fore-
going that the material saturated with the lubricant and adapted to bear against the fabric as the same is fed into the machine, could be mounted on the foot plate in many
10 different ways, for instance the saturated material could be used alone instead of being used in connection with the socket member, but the construction as shown and described is preferable. It is also obvious
15 that this invention is not limited to the precise construction shown in the drawings, as various modifications and alterations may be made therein, by one skilled in the art, within the scope of the appended claims. It
20 is also evident that the device as described is not only adapted for use with a presser foot of the type shown, but that it may be used in connection with any presser foot now in use.

25 I claim:—

1. In combination with a presser foot of a sewing machine, of a conical socket member mounted on said presser foot and adapted to support and retain an absorbent me-
20 dium, said socket member being opened at its lower end to permit of a contact between the absorbent medium and the fabric as the same is fed under said presser foot.
2. A presser foot of the class described comprising means for supporting and retaining an absorbent medium, the lower end of said means conforming substantially to the contour of the under face of the upturned portion of said presser foot.

3. In a presser foot for sewing machines 40 of the flat foot type, having a hinged foot plate, an absorbent medium adapted to be impregnated with a lubricant, a tube-like member disposed upon the forward end of said plate to retain said absorbent material, 45 and means to automatically distribute a portion of said lubricant carried by the absorbent material into contact with a fabric at the moment of passing beneath the forward portion of said foot plate.

50 4. In a presser foot for sewing machines adapted to the sewing of impregnated fabrics, of a hinged foot plate capable of a slight vertical movement to readily pass over inequalities of thicknesses of the fabrics, a tapered tube-like member mounted upon the forward end of said foot plate, absorbent material adapted to be impregnated with a lubricant and disposed within said tube-like member, said foot plate having an 60 upward curve at its forward end, and means for placing the lubricant upon the fabric or fabrics as it passes beneath the forward end of said hinged foot plate.

5. In an attachment of the class described, 65 a presser foot having an upturned portion, a conical socket adapted to support an absorbent medium mounted thereon, the lower end of said socket member extending below the surface of the upturned portion of said 70 presser foot and conforming substantially to the contour of said upturned portion.

In testimony whereof, I affix my signature, in presence of two witnesses.

ALEXANDER LEE HARRISON.
